ASSIGNORS TO PACIFIC PUMP WORKS, OF HUNTINGTON PARK, CALIFORNIA, A
CORPORATION OF CALIFORNIA.

HORIZONTAL PUMP.

Application filed January 13, 1925. Serial No. 2,153.

This invention relates to horizontal centrifugal pumps, and it relates particularly to two-stage pumps of this type. The present form of two stage centrifugal pump generally has a first stage impeller chamber and a second stage impeller chamber, in which first stage and second stage impellers are respectively positioned, these impellers being secured to a shaft which is adapted for driving through suitable means. A suction passage connects with a concentric entrance of the first stage impeller. A fluid such as water enters the suction passage and flows into the impeller entrance. The fluid is engaged by blades of the first stage impeller and is thrown to the periphery of the impeller due to centrifugal force. The fluid leaves the periphery of the first stage impeller, passing into the first stage impeller chamber and from thence it flows into a cross over passage which connects between the periphery of the first stage impeller chamber and a concentric mouth of the second stage impeller chamber. Water enters the mouth of the second stage impeller and is rotated by blades thereof, the water being thrown outward by centrifugal force. The axial pressure of the water against the impellers of the pump tend to move these impellers axially along the shaft on which they are carried, and it is, therefore, necessary to provide means for securing them against axial movement, such means as lock nuts being customary arrangements employed for this purpose. The cross over passage connecting between the first and second stage impeller chambers is generally provided in an extra casting which is bolted to the main body of the pump. It is an object of our invention to provide a horizontal centrifugal pump of the type mentioned in which the pressure against the impellers thereof is substantially in equilibrium. We accomplish this by providing first and second stage impellers which are in the form of an integral rotor. Water from an inlet passage of the pump enters the first stage impeller, and water from a cross over of the pump enters the second stage impeller in such a manner that the water pressure opposing axial movement in the integral rotor is counteracted. This particular construction tends to neutralize the tendency of movement in the rotor. The centrifugal

pump is constructed, however, so that there will be a slight leakage between the impeller chambers. This slight leakage increases the tendency of a movement of the rotor in one direction with respect to the tendency of movement in the other direction, a very slight degree. Due to this arrangement, the rotor can be slidably mounted on its drive shaft and there is a tendency for the rotor to remain in a proper position against an abutment so located that the impellers will be properly positioned in their impeller chambers and so that the rotor will not engage the body of the pump.

It is another object of our invention to provide a centrifugal pump of this character in which the cross over passage which extends between the first and second stage impeller chambers is formed in the main body of the pump. This eliminates an extra casting as was previously necessary. It reduces the cost of the pump, makes the pump more compact, and renders it of a better design.

Other objects and advantages of this invention will appear in the following specification.

With reference to the two sheets of drawings which are for illustrative purposes only,

Fig. 1 is a vertical longitudinal cross section of a two-stage horizontal centrifugal pump taken substantially on the line 1—1 of Fig. 2.

Fig. 2 is an end view of the pump shown in Fig. 1 taken as indicated by the arrow 2 of Fig. 1.

Fig. 3 is a vertical cross section taken through a first stage impeller chamber of the pump, this section being taken substantially on the line 3—3 of Fig. 1.

Fig. 4 is a vertical cross section taken through a second stage impeller chamber of the pump, this view being taken substantially on the line 4—4 of Fig. 1.

The form of our invention shown in the drawings provides a base 11 and a cap 12 which cooperate to provide a main body 13. These members 11 and 12 are provided with flanges 15 and 16, respectively, through which bolts 17 extend in a manner to secure these members together. A first stage impeller chamber 18, and a second stage impeller chamber 19 are provided in the body

13, these first and second stage impeller chambers 18 and 19 being concentric with respect to each other and being separated from each other by a single central wall 20. Concentrically with respect to the chambers 18 and 19 there is provided an opening 21 in the wall 20 which connects between the chambers 18 and 19. Extending concentrically through the chambers 18 and 19 and 10 the opening 21 is a rotor shaft 23. This rotor shaft 23 extends through stuffing boxes 24 and 25 which are provided at opposite sides of the chambers 18 and 19. An arm 27 at the left side of the body 13 carries 15 a bearing box 28, in which ball bearings 29 supporting the left end of the shaft 23 is secured. An arm 31 provided at the right end of the body 13 carries a bearing box 32 which supports a bearing 33, this bearing 33 20 rotatably supporting the right end of the shaft 23. This construction is substantially the same as the bearing construction at the left hand end of the body 13. The right hand end of the shaft 23 extends entirely 25 through the box 32 as shown, and has a flexible connection flange 34 secured at the end thereof, thereby providing a means through which the shaft 23 may be driven.

A rotor 36 is carried by the shaft 23; this 30 rotor has a hub portion 37 which surrounds the shaft 23 and which is secured thereto by means of a gib head key 38 having a gib head 38^a forming an abutment against which the leftward end of the hub 37 engages.

This hub 37 extends through the opening 21 in the central wall 20 and extends into the chambers 18 and 19. A first stage impeller 39 is formed integral with the hub 37 and is positioned in the first stage impeller chamber 18, and a second stage impeller 40 is formed integral with the hub 38 and is positioned in the second stage impeller chamber 19 as shown clearly in Fig. 1 of the drawings. The first stage impeller 35 is provided in the form of a radial wall 42 which extends from the hub 37; a plurality of blades 43; and a radial wall 44, the radial wall 44 being spaced away from the wall 42 by the plurality of blades 43. An annular projection 45 extends concentrically from the radial wall 44 into a suction mouth 46 of the body 13. The second stage impeller 40 includes a radial wall 48 which extends from the hub 37, and a radial wall 49. The radial wall 49 is spaced away from the radial wall 48 by means of a plurality of blades 50. An annular projection 51 extends concentrically from the radial wall 49 into a cross over mouth 53 of the body 13. The 45 annular projection 45 provides a concentric entrance 54 for the first stage impeller 39 and the annular projection 51 provides a concentric entrance 55 for the second stage impeller 40.

60 A suction passage 58 is provided in the body 13, this suction passage 58 connecting with the suction mouth 46 of the body 13. A cross over passage 60 is formed in the body 13. This cross over passage 60 as shown in Figs. 1, 3 and 4 connects between the periphery of the first stage impeller chamber 18 and the concentric cross over mouth 53 of the body 13. As is evident from the drawings, this cross over passage 60 extends from the first stage impeller 75 chamber 18 around the second stage impeller chamber 19 to the cross over mouth 53. An exhaust passage 63 connects with the periphery of the second stage impeller chamber 19 as clearly shown in Fig. 4 of the 80 drawings.

Water or any other fluid enters the suction passage 58 through suitable means such as piping 64 which is connected to the body 13 as shown in Fig. 2. This water passes through the suction passage 58 and enters the concentric entrance 54 of the first stage impeller 39. The shaft 23 and rotor 38 at this time are rotated at a high rate of speed. By reason of engagement of the water by 90 the blades 43, the water is given rotation. Centrifugal force, due to this rotation, throws the water outward through the impeller 48 at a high velocity into the periphery of the first stage impeller chamber 18. 95 The water passes from the periphery of the first stage impeller chamber 18 into the cross over passage 60. From the cross over passage 60, the water passes into the concentric entrance 55 of the second stage impeller 40. The water is engaged by blades 50 of this impeller and is caused to rotate. Centrifugal force throws the water outward from the impeller at a high velocity into the second stage impeller chamber 19. The 100 water flows around the periphery of the second stage impeller chamber 19, and passes therefrom into the exhaust passage 63 and is carried therefrom by suitable means such as a pipe 66 which is connected to the body 105 13 as shown in Fig. 4 of the drawings.

By inspection of Fig. 1 it is evident that the water entrances 54 and 55 of the first and second stage impellers 39 and 40 are extended in opposite or opposing directions. It is likewise evident that water entering these entrances 54 and 55 passes therewith in opposing directions. Water pressure in the first stage impeller chamber 18 produces a tendency for the first stage impeller 39 to move in a leftward direction, and the water pressure in the second stage impeller 19 produces a tendency for the second stage impeller 40 to move in a rightward direction; that is, the tendency for the impellers 39 and 40 is to move in opposite directions. The opening 21 in the central wall 20 is made slightly larger than that portion of the hub 37 which extends therethrough. This is in 115 120 125 130

tentionally provided thusly, so that there will be a slight leakage from the high pressure chamber 19 into the low pressure chamber 18. If there were no leakage between these chambers, the tendency of movement of the impellers 39 and 40 in opposite directions would be equalized, this being due to the well known thrust ratio for opposed double stage centrifugal pumps of this general type, in which the discharge pressure of the first stage less the intake pressure thereof denotes thrust towards the intake end of the pump and in which the discharge pressure of the second stage less the intake pressure thereof denotes thrust in the opposite direction. If the pump herein illustrated were not provided with interchamber leakage the thrust equation would be $P_{18} - P_{54} = P_{19} - P_{55}$, in which P denotes pressure, and in which the numerals are reference characters in Fig. 1 and used in the equation to designate the respective intakes and discharge portions of the two stages. However, as it is not desired to have the rotor in equilibrium, the interchamber leakage is provided to lower P_{19} , thereby decreasing the right thrust of the high pressure stage and to increase P_{18} , thereby increasing the left thrust of the low pressure stage, with a resulting predominant left thrust for the complete pump. There is then a very slight tendency for the rotor 36 to move in a leftward direction. The leftward end of the hub 37 as previously mentioned, engages the gib head 38 of the key 38 which prevents a movement of the rotor 36; however, when the rotor is being rotated, the rotor 36 always pressurably engages with the gib head 38^a. This is extremely desirable owing to the fact that it retains the rotor 36 in a proper working position. The rotor is retained in the position shown in the drawings so that the impellers are centralized in their impeller chambers and so that the rotor is not engaged with the body 11 of the pump at any point. If the rotor were exactly in equilibrium, there would be a freedom thereof relative to the shaft, and the rotor would remain not in a certain position, but in any position into which it is forced during the starting of the pump. The rotor might at this time engage with the body of the pump, causing considerable friction and wear.

From the drawings it is obvious that the shaft 23 of the pump of my invention is uniformly cylindrical and is of the same diameter throughout except at the left hand end thereof. There is no extensive machine work necessary on this shaft as is necessary on those pumps which require the use of locking rings and other securing means for the rotor. The gib head key 38 is the only securing which is required for the rotor

in my invention. The shaft 23 is reversible and makes the pump convertible from a right hand drive into a left hand drive pump. This is possible because of the fact that the shaft is uniformly cylindrical, and there are no formations which would interfere if the shaft 23 were reversed.

It is a feature of the invention to provide a novel arrangement which includes the cross over passage 63. Our invention is so designed that it is possible for us to form the cross over passage 60 in the main body 13 of the pump. We accomplish this by reason of the compactness of design of our invention. By being able to form the cross over passage 60 within the body 13, it is possible for us to produce an efficient pump at a cheaper cost than pumps of this type which require an extra casting which is bolted to the main casting for the cross over of the pump. The elimination of an extra casting also contributes to superiority in design, making a pump which is of better appearance and more compact than other pumps.

Although we have described and delineated our invention in the form of a two-stage centrifugal pump, we wish it to be clearly understood that we may employ our invention in pumps having more stages and other designs without departing from the spirit and scope of this invention.

We claim as our invention:

1. In a centrifugal pump, the combination of: a housing forming a first stage impeller chamber and an adjacent second stage impeller chamber; a drive shaft extending through said chambers; a rotor carried by and slidable on said shaft, said rotor comprising first and second stage impellers positioned respectively in said first and second stage chambers; and a key rotatably connecting said rotor to said shaft and formed to provide an abutment limiting the sliding of the rotor on the shaft in one direction.

2. In a centrifugal pump, the combination of: a housing forming a first stage impeller chamber and an adjacent second stage impeller chamber separated by a wall having an axial opening; a drive shaft extending through said chambers and said opening; a rotor carried by and slidable on said shaft, said rotor comprising a hub surrounding the shaft and extending through said opening and first and second stage impellers extending from said hub into the respective chambers; and a key rotatably connecting said rotor to said shaft and formed to provide an abutment to be engaged by one end of said hub to limit the sliding of the rotor on the shaft in one direction.

3. In a centrifugal pump, the combination of: a housing forming a low pressure

- impeller chamber having a suction inlet, a high pressure impeller chamber having a discharge outlet, a cross-over passage connecting the low pressure chamber outlet with the high pressure chamber inlet, and a wall separating said chambers and having an axial opening; a drive shaft extending through said chambers and said axial opening; a rotor carried by and slidable on said shaft, said rotor comprising a hub surrounding the shaft and extending through said opening and low and high pressure impellers extending from said hub into the respective chambers; and a key rotatably connecting said rotor to the shaft and formed to provide an abutment to be engaged by one end of said hub to limit the sliding of the rotor on the shaft in one direction, said opening being of a diameter larger than said hub to permit constant leakage from the high to the low pressure chambers to insure an axial thrust sufficient to maintain the rotor hub in engagement with said abutment.
4. In a centrifugal pump, the combination of: walls forming an impeller chamber having an inlet and an outlet passage; a shaft extending concentrically through said impeller chamber; a rotor carried by said shaft in said impeller chamber; and a key rotatably connecting said rotor with said shaft and having a head forming a stop, said rotor being slidable on said shaft and held against said head of said key by the pressure of a fluid passing into said impeller chamber through said inlet passage.
5. In a centrifugal pump, the combination of: a housing forming a low pressure chamber and an adjacent high pressure chamber; a drive shaft extending through said chambers; opposed impellers carried by and in driving relation with said shaft, one of said impellers being positioned in each chamber; and means providing leakage from said high pressure chamber to said low pressure chamber to at all times insure a predominant axial thrust of the impellers towards the low pressure chamber.
6. In a centrifugal pump, the combination of: a housing forming a low pressure chamber and an adjacent high pressure chamber; a drive shaft extending through said chambers and provided with an abutment; impellers slidable on said shaft and rotatable therewith, one of said impellers being positioned in each chamber; and means providing interchamber leakage insuring a predominant axial thrust of the impellers towards said abutment.
7. In a centrifugal pump, the combination of: a chamber; a drive shaft extending into said chamber and having an abutment; and an impeller slidable on said shaft and rotatable therewith and positioned within said chamber, said impeller being adapted to exert an axial thrust maintaining it in engagement with said abutment.
8. In a centrifugal pump, the combination of: a housing forming a low pressure chamber and an adjacent high pressure chamber; a drive shaft extending through said chambers; and opposed propellers carried by and in driving relation with said shaft, one of said impellers being positioned in each chamber and the housing being formed to provide leakage from said high pressure chamber to said low pressure chamber to at all times insure a predominant axial thrust of the impellers towards the low pressure chamber.
9. In a centrifugal pump, the combination of: a housing forming a low pressure chamber and an adjacent high pressure chamber; a drive shaft extending through said chambers and provided with an abutment; and impellers slidable on said shaft and rotatable therewith, one of said impellers being positioned in each chamber and the housing being formed to provide interchamber leakage insuring a predominant axial thrust of the impellers towards said abutment.
10. In a multi-stage centrifugal pump of the opposed impeller type, the combination of: a housing forming a low pressure chamber and a high pressure chamber; a drive shaft extending through said chambers; and impellers mounted in driving relation on said shaft and positioned in the respective chambers, said chambers and impellers being relatively proportioned to cause an equalized axial thrust of the impellers in opposite directions and the parts being formed to provide an interchamber leakage insuring a predominant axial thrust in one direction.
- In testimony whereof, we have hereunto set our hands at Los Angeles, California, this 8th day of January, 1925.
- MICHAEL E. WALTERS.
ARTHUR R. WEIS.
